UNITED STATES PATENT OFFICE.

ANDREW J. SANFORD, OF NEWARK, OHIO, ASSIGNOR TO A. H. HEISEY & CO., OF NEWARK, OHIO.

DESIGN FOR A PITCHER.

52,347.

Specification for Design. Patented Aug. 27, 1918.

Application filed May 26, 1916. Serial No. 100,159. Term of patent 14 years.

To all whom it may concern:

Be it known that I, ANDREW J. SANFORD, a citizen of the United States, residing at Newark, Ohio, have invented a new, original, and ornamental Design for a Pitcher, of which the following is a specification, reference being had to the accompanying drawing, forming part thereof.

In the drawing:
Figure 1 is a front elevation.
Fig. 2 is a side elevation, and
Fig. 3 is a top plan of a pitcher embodying the invention.

I claim:
The design for a pitcher, as shown.
ANDREW J. SANFORD.
